UNITED STATES PATENT OFFICE.

ELIZABETH F. PACKARD, OF DORCHESTER, MASSACHUSETTS.

DESIGN FOR A COMBINATION WASH CLOTH AND CAKE OF SOAP.

60,258.

Specification for Design. Patented Jan. 17, 1922.

Application filed May 13, 1921. Serial No. 469,390. Term of patent 3½ years.

To all whom it may concern:

Be it known that I, ELIZABETH F. PACKARD, a citizen of the United States, residing at Dorchester, in the county of Suffolk and Commonwealth of Massachusetts, have invented a new, original, and ornamental Design for a Combination Wash Cloth and Cake of Soap, of which the following is a specification, reference being had to the accompanying drawing, forming part thereof.

Fig. 1 is a face view of a combination wash cloth and cake of soap showing my new design.

Fig. 2 is a side view thereof.

I claim:

The ornamental design for a combination wash cloth and cake of soap, as shown.

ELIZABETH F. PACKARD.
